UNITED STATES PATENT OFFICE

HENRY VAN DEEST, OF FREEPORT, ILLINOIS, ASSIGNOR TO HENNEY MOTOR COMPANY,
OF FREEPORT, ILLINOIS, A CORPORATION OF DELAWARE

COT FASTENER FOR AMBULANCES

Application filed March 23, 1931. Serial No. 524,486.

This invention relates to cot fasteners for use in ambulances and other vehicles.

Cot fasteners have been available in various forms but have been subject to one or 5 more serious objections. In some cases the fasteners were apt to allow movement of the cot, especially if the vehicle were to suddenly slow down or make a sharp turn, and with certain constructions such movement was apt 10 to cause unfastening of the cot. Then, too, there has been the objection with most cot fasteners that the fastening and unfastening of the cot is not as handy as desired and takes up too much time. It is, therefore, the 15 principal object of my invention to provide cot fasteners which not only positively lock the cot in position but are so arranged and constructed that the fastening and unfastening of the cot can be attended to easily from 20 a remote point, as for example, from the rear door of an ambulance.

The invention is illustrated in the accompanying drawings, wherein—

Figure 1 is a plan view showing cot fasteners made in accordance with my invention in 25 a typical ambulance installation;

Fig. 2 is a side view;

Fig. 3 is a horizontal sectional detail of 30 the rear fastener on the line 3—3 of Fig. 2 on an enlarged scale;

Fig. 4 is a cross-section on the line 4—4 of Fig. 3, and

Figs. 5 and 6 are two views of the handle end of the rear fastener.

35 The same reference numerals are applied to corresponding parts throughout the views.

The numerals 9 and 10 indicate the side wall and floor, respectively, of the ambulance or other vehicle in which the cot shown at 11 40 is to be fastened in place. The cot may be of any suitable or preferred construction, that shown being of the conventional form providing front and rear legs 12 and 13, respectively, by means of which the same may 45 be conveniently fastened to the side wall 9. As usual, wheels 14 are provided on the cot to permit it to be rolled into and out of position on the floor 10 in the ambulance. The wheels are preferably mounted as at 15 so as 50 to caster and thus permit sidewise movement

at will. Two fasteners are provided, a front fastener 16 and a rear fastener 17 arranged to cooperate with the legs 12 and 13, respectively, to fasten the cot to the side wall 9.

It is evident in Figs. 1 and 2 that the front 55 fastener 16 comprises a cast body 18 suitably secured by its base portion, as at 19, to the side wall and formed to provide a rearwardly facing hook 20 for reception therein of the front leg 12 of the cot. The body 18 is suitably 60 formed with an inclined guide surface 21 extending forwardly and outwardly with respect to the wall 9, toward the recess in the hook 20, whereby to guide the front leg 12 into the hook as the cot is moved into position for fastening. When the leg 12 is engaged in the hook 20, forward movement as 65 well as lateral movement of the cot is prevented.

The rear fastener 17 comprises a housing 70 22 fastened by its base portion, as at 23, to the side wall 9 of the ambulance. A forwardly facing hook 24 has an elongated shank portion 25 formed integral therewith on which a lug 26 is provided projecting into 75 the housing 22 for slidably mounting the hook 24 on the housing. A rod 27 passes through a hole 28 in the lug 26 and is slidably received in registering holes 29 and 30 provided in the opposite end walls of the 80 housing 22. The lug 26 is fastened rigidly to the rod 27, as at 31, and a coiled compression spring 32 fits about the rod 27 in the housing 22 and has abutment at one end with the end wall of the housing 22 and at its other 85 end with the lug 26, whereby normally to urge the hook 24 forwardly for locking engagement with the rear leg 13 of the cot. Felt, leather, or any other suitable cushioning material may be provided on the inside 90 of the hooks 20 and 24, as appears at 33 in Fig. 3. While the spring 32 serves normally to urge the hook 24 into engagement with the rear leg 13 whereby to hold the cot between the hooks 20 and 24, I have provided 95 manually operable means for quickly releasably securing the hook 24 in a retracted open position against the action of the spring 32 to permit the leg 13 to be moved into or out 100 of position in the fastening and unfastening

of the cot, and, as will also appear, have so constructed said means whereby the hook 24 may be also quickly releasably locked in the closed position shown in Fig. 3. This means will now be described.

5 The housing 22 for the hook 24 is preferably fastened with the one end of an elongated plate 34 to the side wall 9 of the ambulance, and the rod 27, which extends rearwardly from the housing 22, is of sufficient length to reach clear beyond the foot end of the cot for connection with a handle 35 that cooperates with a bracket 36 fastened with the other end of the plate 34 to the side wall 9, as at 37. The bracket provides a guide 38 at one end thereof for the end of the rod 27, and another guide 39 at the other end thereof for a rearwardly projecting cylindrical shank portion 40 on the handle 35. The end 20 of the rod 27 is suitably threaded in the handle 35, as at 41, to allow for adjustment of the rod with respect to the handle, or vice versa. A lug 42 projects laterally from the bracket 36 below the shank 40 and is so located that the handle 35 is arranged to be swung downwardly in front of the same when the hook 24 is in closed position, whereby to positively lock the hook in that position, and, on the other hand, is arranged to 25 be swung downwardly behind the same when the handle has been moved to the rear to the dotted line position shown in Fig. 5, whereby to positively lock the hook 24 in open position. The lug 42, therefore, serves a double 30 purpose.

In operation, when the cot is rolled into position in the ambulance for fastening, the front leg 12 is brought into engagement with the hook 20 of the front fastener 16, which 40 prevents further forward movement of the cot, whereupon the rear end of the cot is moved sidewise to bring the rear leg 13 into abutment with the side of the shank 25 of the hook 24. Then, the handle 35 is swung upwardly to clear the lug 42, whereupon the spring 32 snaps the hook 24 into engagement with the leg 13 from behind the same. This 45 it will be understood more or less firmly fastens the cot in place, but to make certain that 50 the cot cannot become unfastened accidentally, the handle 35 is arranged to be swung downwardly in front of the lug 42 to positively lock the hook 24 in closed position. It is, therefore, obvious that no matter how 55 suddenly the ambulance slows down or starts up, and no matter how sharply corners are turned, there is no way for the cot to work loose, and that is, because there is no possibility of its having any movement whatsoever. Even slight movement is objectionable 60 because of the jostling back and forth and the noise that goes with it, all of which would be more or less distressing to the person on the cot. In most other cot fasteners with which 65 I am familiar, there is no possibility of fas-

tening the cot so rigidly as herein disclosed, and certain cot fasteners are so constructed that extreme movement of the cot, especially if attended with side sway of the ambulance, is quite apt to cause the cot to become unfastened. When the ambulance arrives at its destination, the attendant simply swings the handle 35 upwardly to clear the lug 42 and then pulls back on the handle and swings it down behind the lug to move the hook 24 to retracted open position against the action of the spring 32. The hook is thereby locked in open position, and the attendant removes the cot by simply moving the rear end sidewise to clear the hook 24, whereupon the cot can be rolled away from the hook 20 and out of the ambulance. It is believed to be clear from the description how quickly and easily the matter of fastening and unfastening can be attended to.

I claim:

1. In fastening means for a cot or the like comprising a pair of spaced bases suitably supported adjacent the front and rear portions of a cot to be fastened, a hook projecting rigidly from the one base and facing in one direction to hold one portion of the cot, a companion hook projecting from the other base and facing in the opposite direction to hold the other portion of the cot, and means for slidably mounting the last mentioned hook on its base for movement toward and away from the first hook, spring means on said base normally urging the slideable hook to move relative to the base in one direction to hold the cot portion thereon, a rod fixed to said hook and extending from the base to an operating point, a handle on said rod at the operating point, and stop means for abutment with the handle to hold the same in either one of two positions, the handle in one position being held by the stop means to prevent movement of the hook by the cot against the action of the spring means, and the handle being held by the stop means in its other position to hold the hook in retracted position and against movement under action of the spring means.

2. In fastening means for a cot or the like comprising a pair of spaced bases suitably supported adjacent the front and rear portions of a cot to be fastened, a hook projecting rigidly from the one base and facing in one direction to hold one portion of the cot, a companion hook projecting from the other base and facing in the opposite direction to hold the other portion of the cot, and means for slidably mounting the last mentioned hook on its base for movement toward and away from the first hook, spring means on said base normally urging the slideable hook to move relative to the base in one direction, a rod fixed to said hook and extending from the base to an operating point, a handle on said rod at the operating point, and stop

means for abutment with the handle, to hold the same in either one of two positions, in one position being held by the stop means to prevent movement of the hook by the cot from cot holding position.

- 5 3. In fastening means for a cot or the like comprising a pair of spaced bases suitably supported adjacent the front and rear portions of a cot to be fastened, a hook projecting rigidly from the one base and facing in one direction to hold one portion of the cot, a companion hook projecting from the other base and facing in the opposite direction to hold the other portion of the cot, and means for slidably mounting the last mentioned hook on its base for movement toward and away from the first hook, a rod fixed to said hook and extending from the base to an operating point, a handle on said rod at the operating point, and stop means for abutment with the handle to hold the same in either one of two positions, the handle in one position being held by the stop means to prevent movement of the hook by the cot from cot holding position, and the handle being held by the stop means in its other position to hold the hook in retracted position.

CERTIFICATE OF CORRECTION.

Patent No. 1,858,530.

May 17, 1932.

HENRY VAN DEEST.

It is hereby certified that error appears in the printed specification of the above numbered patent requiring correction as follows: Page 3, lines 1 and 2, claim 2, strike out the words and comma "to hold the same in either one of two positions," and insert instead the handle; and that the said Letters Patent should be read with this correction therein that the same may conform to the record of the case in the Patent Office.

Signed and sealed this 12th day of July, A. D. 1932.

(Seal)

M. J. Moore,
Acting Commissioner of Patents.
